UNITED STATES PATENT OFFICE.

JOHN V. RUND, OF PESOTUM, ILLINOIS.

TRIP MECHANISM.

1,115,579.

Specification of Letters Patent. Patented Nov. 3, 1914.

Original application filed January 31, 1913, Serial No. 745,471. Divided and this application filed September 3, 1913. Serial No. 788,869.

To all whom it may concern:

Be it known that I, JOHN V. RUND, citizen of the United States, residing at Pesotum, in the county of Champaign and State of Illinois, have invented certain new and useful Improvements in Trip Mechanism, of which the following is a specification.

My invention relates to new and useful improvements in tripping devices, and more particularly to trips employed in connection with railways for actuating a brake or other safety operating appliance carried by locomotives, being a division of my co-pending application for an automatic railway appliance, filed January 31, 1913 and bearing the Serial No. 745,471.

The object of my invention is the provision of a trip which may be readily swung into and out of active position and which may be connected to the usual semaphore employed in signaling trains, in order that the semaphore may be swung to danger position whenever the trip is swung to active position.

A further object of my invention is to provide means for swinging the trip and semaphore arm in and out of active or danger position simultaneously. And, a still further object of my invention is to provide a trip which will gradually engage the mechanism to be tripped and thus avoid injury thereto.

With these and other objects in view, my invention will be more fully described, illustrated in the accompanying drawings, and then specifically pointed out in the claims which are attached to and form a part of this application.

In the drawings:—Figure 1 is a transverse sectional view through a conventional track in connection with which my trip is employed, showing the trip and its operating mechanism in elevation, the housing of the operating mechanism being shown in section. Fig. 2 is a sectional view on the line 2—2 of Fig. 1, further showing the construction and manner of mounting the trip. Fig. 3 is a perspective view of the trip proper.

Corresponding and like parts are referred to in the following description and indicated in all the views of the accompanying drawing by the same reference characters.

To insure a clear understanding of my trip mechanism I have illustrated the same

in connection with a conventional track, including spaced rails 10 carried by ties 11. The trip device proper, as best shown in Fig. 3 of the drawings, comprises a longitudinally bowed body-member 12 having downwardly depending parallel end-portions 13 and 14 provided with aligned openings 15. The end portion 14 is provided with a lateral extension 16 terminating in an arm 17 parallel to the end portion 14 but offset therefrom, the extension 16 and arm 17 in effect, forming a lever arm for swinging the trip when the latter is mounted in place.

The trip is mounted in spaced parallel relation to one rail of the track by means of brackets 18 having reduced threaded terminals 19 which pass through bores formed in the web of the rail and which receive nuts 20 by which the brackets are secured in place. The opposite ends of the brackets, however, terminate in spaced arms 21 between which the end portions 13 and 14 of the trip are pivoted, pivot pins 22 being passed through the arms and the trip ends, as shown in Fig. 2 of the drawings.

From the foregoing description it will be apparent that when the trip operating arm 17 is swung in a vertical position, the bowed or arched portion 12 of the trip will be directed upwardly as shown in Figs. 1 and 2, the trip as a whole, lying in a vertical plane parallel to the plane of the adjacent rail. It will further be apparent that the operating arm 17 of the trip may be swung inwardly and upwardly toward the rail to swing the trip to horizontal position. This trip, of course, is so proportioned that when in the latter position it will offer no obstruction to the passage of any train-carried device which it is to engage when in active position. When in active position any train-carried device which it is to trip will strike against one end of the trip and ride upwardly over the bowed portion of the same and then down over the opposite end, the action of the trip being only momentary.

In order to operate this trip to swing the same into and out of active position, as required, I preferably provide a housing 23 leading from directly beneath the trip-operated arm 17 to any suitable signaling station, conventionally shown at 24. Within this station I have provided an arcuate bracket 25 having spaced rack-teeth 26 for

engagement by the spring-pressed pawl 27 of a hand-lever 28 which is pivotally mounted intermediate its length, as shown at 29. The free end of this hand-lever is pivotally connected to a link 30 one end of which extends into the housing 23 and is pivotally connected to one arm of a bell-crank lever 31 which is pivoted as at 32 within the housing. A connecting rod 33 pivotally connects the free arm of the lever 31 with the free end of the operating arm 17 of the trip. It will therefore be apparent that when the operating lever 28 is swung downwardly, its movement is transmitted through the link 30, lever 31 and connecting rod 33 to swing the trip to active position, while when the operating lever 28 is raised the trip will be swung in the reverse direction, or to inactive position.

In order to provide means for displaying a signal to warn the engineer of an approaching train that the trip is set in active position so that he may stop the train before reaching the trip, if desired, I provide a standard 34 carrying at its upper end a swingingly mounted semaphore arm 35 having an angularly disposed operating arm 36. A connecting rod 37 is pivotally connected by one end with the free end of this semaphore arm and by its opposite end to one arm of a bell-crank lever 38, which is pivotally mounted within the housing 23, as shown at 39. The opposite arm of this bell-crank lever is slotted, as shown at 40, to seat a pin 41 carried by the connecting rod 33. It will therefore be apparent that the movement of the connecting rod in raising or lowering the trip will be transmitted through the lever 38 and connecting rod 37 to correspondingly raise or lower the semaphore arm, the movement of the trip and arm being simultaneous.

From the foregoing description taken in

connection with the drawings, the operation of the trip and the manner in which such operation acts to operate the semaphore arm will be readily understood and no description of the same is necessary.

It will of course be understood that various changes in details of construction may be made, within the scope of the appended claims, without in the slightest degree departing from the spirit of my invention.

What I claim is:—

1. A tripping device for operating train-carried safety devices including a trip proper swingingly mounted upon a rail and movable about an axis parallel with the rail, means including a connecting rod for operating said trip, a pin carried by the connecting rod, a pivoted bell crank lever having a slotted arm engaging said pin, a swingingly mounted semaphore arm, and operative connection between said semaphore arm and the unslotted arm of the bell-crank lever.

2. A tripping device for operating train-carried safety appliances, including a swingingly mounted trip, a swingingly mounted lever, a bell-crank lever, a link connecting the first lever and bell-crank lever, a connecting rod joining the bell-crank lever and trip, a pin carried by the connecting rod, a second bell-crank lever having a slotted arm engaging the pin, a swingingly mounted semaphore arm, and a rod connecting the semaphore arm with the unslotted arm of the second bell-crank lever.

In testimony whereof I affix my signature in presence of two witnesses.

JOHN V. RUND. [L.S.]
